BAG CLOSURE

Robert Debate, New Orleans, La., assignor to
Bemis Bro. Bag Company, St. Louis, Mo., a corporation of Missouri

Application January 17, 1944, Serial No. 518,549

1 Claim. (Cl. 150—11)

This invention relates to bag closures, and with regard to certain more specific features to open-mesh bag closures incorporating pre-woven draw cords.

Among the several objects of the invention may be noted the provision of an open-mesh bag having a draw cord, which may readily be manufactured from a web of open-weave material in which a draw cord has previously been woven, without the necessity for knotting the draw cord subsequently to bag formation; the provision of a bag closure of the class described in which a narrow draw cord may, without knotting, be securely and automatically anchored at the time that a side seam is formed; the provision of a construction of the class described which is effective with the coarse type of stitching required for open-mesh seam formation; and the provision of a structure of this class which provides the desired results at a saving in manufacturing cost. Other objects will be in part obvious and in part pointed out hereinafter.

The invention accordingly comprises the elements and combinations of elements, steps and sequence of steps, features of construction and manipulation, and arrangements of parts which will be exemplified in structures and methods hereinafter described, and the scope of the application of which will be indicated in the following claim.

In the accompanying drawings, in which is illustrated one of various possible embodiments of the invention:

Fig. 1 is a plan layout of a segment of open-mesh web material from which bags are to be made, with indications thereon of certain lines of severance and folding;

Fig. 2 is a plan view of a severed segment of material folded preparatory to applying bottom and side seams;

Fig. 3 is an enlarged fragmentary view showing application of stitching to complete a bag, a small section of the otherwise conventional warp threads being shown in detail;

Fig. 4 is an enlarged edge view from line 4—4 of Fig. 3;

Fig. 5 is a fragmentary corner view similar to the upper right-hand corner of Fig. 3, but disclosing an alternative embodiment;

Fig. 6 is an enlarged edge view from line 6—6 of Fig. 5;

Fig. 7 is a view similar to Fig. 5 showing still another embodiment; and

Fig. 8 is an enlarged edge view from line 8—8 of Fig. 7.

Similar reference characters indicate corresponding parts throughout the several views of the drawings.

Fruits, vegetables and the like are often packed in so-called open-mesh bags in which are draw strings which allow closure of the bags after

filling. The bag-forming fabric is generally cut as a segment from a web of open-weave material, in which the draw cord is pre-woven. The resulting segment is folded over once and then 5 seamed to form a bottom and a side seam. It will be noted that the cutting which occurs along line C leaves raw edges which are brought together for the seaming operation, and that the raw cut ends of the draw cord 11 form a part of these raw edges.

The stitching used for the seam is quite coarse in order to form a proper cooperation with the open-mesh characteristic of the material being seamed. The result is that a desired cooperation 15 between the seam and the loose ends of the draw cord is not consummated, as desired. Thus, in order to avoid pulling out of the draw cord it has been tied. The tying operation is tedious, time consuming and expensive.

20 In the fabric supply web 1 of Fig. 1 the warp threads 3 are parallel to the length of the web and the filling threads 5 are cross-wise, thus placing the selvages 7 and 9 at the edges of the web. The pre-woven draw cord is shown at 11 25 parallel to the web length and near one edge. Beyond the draw cord the warp threads are more closely woven for added strength. They are also more closely woven near the bottom, for similar reasons. To make a bag the web is cut cross-wise into segments as at lines C. Each resulting segment is then folded on a median cross-wise fold line F. Later it is seamed along the bottom and along the adjacent cut edges to form a bag as will appear. Thus the selvages 7 and 9 are at 30 the desired mouth and bottom of the bag respectively. The draw cord 11 is also near the mouth. One edge closure of the bag is formed by the fold line F and the other edge closure by the side seam to be applied.

35 40 As detailed in a small part of Fig. 3 the warp thread in web 3 may consist in elements A and B alternately woven over and under the filler threads 5 to form what is known as a leno weave. This is not absolutely necessary as will appear in Figs. 5 and 7 wherein plain warp threads are illustrated. The web 1 is in a continuous supply. The draw cord 11 is also continuous in the web, and, for example, is woven alternately over and under six of the filler threads.

45 50 Heretofore, the draw cord was not anchored by the stitching because the stitching ordinarily used in the seam is so coarse that there is no assurance that it will engage the draw cord.

55 After the continuous web 1 has been cut along lines such as illustrated at C and the resulting segment folded along line F as indicated in Fig. 2, stitching is applied along the bottom as indicated at 13 and along the non-folded side as indicated at 15. The lengths of stitching 13 and 15 60 may be continuous as indicated.

Instead of carrying the stitching 15 straight over an unfolded corner of the bag (for an unfolded upper right-hand corner in Fig. 2), said right-hand corner is folded over as indicated at 17 and then under as indicated at 19 (Figs. 3 and 4), to form at said corner six plies of bag material as a tight bundle. It will be seen that since the draw cord 11 was woven into the open-mesh fabric that it also at the corner will be folded over and under so that it will be traversed by the stitching 15 at six points. The stitching 15 may be angled as indicated at 21 to follow the length of the resulting folded-over triangular bundle of material. Coarse stitching is ordinarily used for the threads 13, 15 because it is best adapted to hold open weave fabric. For example, it is common practice to use about five or six stitches per inch for seaming an open-mesh fabric having $\frac{1}{8}$ inch interstitial lattices between web and filler threads. Such a coarse stitch would not consistently anchor loose ends E of the draw cord 11, but will anchor these ends if they are turned over in a bundle as described. Thus consistent anchoring of the end E of the draw cord 11 is obtained by bundling the corner region of the bag in the vicinity of and including said draw cord ends E.

In Figs. 5 and 6 is shown a modification in which the corner portion of the bag, including the ends E of the draw cord 11 are simply folded over once, without the additional under folding step of Fig. 3. In this case the stitching 15 at the corner of the bag traverses four layers of open-mesh fabric and four end portions of the draw cord 11. This form of the invention is satisfactory where the open-mesh fabric has smaller lattices and/or where the stitching 15 is finer. The same bundling principle is the cause of the efficient anchoring.

Figs. 7 and 8 show still another four-layer form of the invention in which, instead of folding the two sides of the corner portion all in the same direction, they are folded oppositely against opposite sides of the bag near its mouth. The folds are triangular as before, but each lies against an opposite side of the bag and carries with it one end length of the draw cord 11. The object of the invention is again accomplished because the stitching 15 at the corner of the bag traverses a bundle of four layers of open mesh fabric, and four parts of the draw cord. The form of the invention shown in Figs. 7 and 8 has been practically applied to open-mesh fabrics which are not of the leno weave type. Such fabrics have the filler threads 25 of the same single type as the warp threads 23, that is, plain threads simply interweave with one another instead of the web threads being compound and woven alternately over and under the filler threads.

The invention is particularly useful in quantity manufacture because all that an operator needs to do is to make the turned-over bundle at the corner of the bag as the seam-forming needle of the sewing machine is approached while guiding the bundled fabric so that the stitching properly traverses it, including the draw cord and portions. Thus with very little effort and expense the draw cord is anchored very securely. The costly draw cord tying operation is eliminated entirely.

The stitching 15 may be of the single strand variety or made up of several strands, for example, two 3-ply 16-yarn braided threads. These may be threaded through the eye of the sewing

needle and their use reduces slipping between the sewing thread and the open-mesh fabric.

It is to be understood that the bag before it is put into final use is turned inside out from the condition shown in Figs. 3-8.

It will also be understood that the bag may be made up by cutting instead of folding at F and then superimposing the two layers thus separated and seaming on both sides at the resulting raw edges. In such event a turned-over bundled portion should be provided at each upper corner of the bag to be traversed by the respective seams on opposite sides of the bag.

The shown round character of the draw cord 11 is better than flat draw cords such as ribbons and the like which are expensive and not as satisfactory for the purpose. A round draw cord functions better, and is stronger than a flat ribbon-like draw cord and is not subject to distortion under twist. The present invention solves the problem which has heretofore made round draw cords useless unless tied. However, it also improvedly anchors flat draw cords when treated as herein specified.

One item that makes the invention so economical to produce is that the local triangular folding at the corner, including the raw cut edges of the draw cord 11, may be made with slight effort as the needle which produces the stitching 15 is approached, the stitching carrying on right on through the folded portion during the stitching operation which produces the side seam. The triangular portions which are folded against the bag at its corner carry angled woven ends of the draw cord as indicated in Figs. 3, 5 and 7. These angled draw cord portions are not in line with the remainder of the draw cord. Thus they, in a flatwise plane, present adjacent draw cord portions for better interception by the stitching which traverses the folded triangular portion. The result is a greater certainty of catching at least some portions of the ends of the draw cord positively to anchor it.

The term bundle as used herein describes all of the corner foldings shown in Figs. 3-8.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

55 I claim:

In a bag having sides cut from an open-mesh woven web and having a prewoven and also cut draw cord near the mouth-forming edge, comprising a stitched plain non-folded side seam adjacent the raw cut edges throughout most of their lengths, said raw cut edges being angularly locally folded against the bag adjacent to the cut ends of the draw cord at an end of the bag mouth, triangular portions of the web being thus formed against the bag and carrying angled woven ends of the draw cord which lie near but not in line with the remainder of the draw cord so as flatwise to present adjacent draw cord portions for better interception by stitching, the stitching of the side seam traversing said folded triangular portions, and by reason of the angled end portions of the draw cord being adapted to catch at least some portions at the end portions of the draw cord positively to anchor the same.

ROBERT DEBATE.
